UNITED STATES PATENT OFFICE.

EMANUEL RUSCH, OF POTTENDORF, NEAR VIENNA, AUSTRIA.

BLEACHING COTTON IN THE FORM OF COPS.

SPECIFICATION forming part of Letters Patent No. 254,386, dated February 28, 1882.

Application filed September 27, 1881. (No model.)

To all whom it may concern:

Be it known that I, EMANUEL RUSCH, of Pottendorf, near Vienna, in the Empire of Austria, have invented certain new and useful Improvements in Bleaching or Dyeing Yarn in Cops, of which the following is a specification.

Heretofore it has not, so far as known to me, been practicable to produce bleached or dyed cops of uniform color and without any waste of material by reason of unequal or imperfect bleaching or dyeing; and the object of my invention is to enable this to be done in the same simple way that yarn is bleached or dyed in hanks. The cops cannot be properly bleached or dyed on the spindles on which they are wound, because the swelling of the yarn when wet will cause the cop to tightly hug the spindle, and thereby compact the yarn and prevent the bleaching or other liquid from reaching the interior of the cop, and even if the cop be wound on a fluted or grooved spindle, or transferred after winding to a fluted or grooved spindle of the same diameter as that on which it was wound, the shrinking of the yarn will cause it to hug the ridges between the flutes or grooves, and thereby not only compact the yarn on the ridges themselves, but also produce a tension on the yarn across the flutes, and so prevent the bleaching or other liquid from thoroughly and evenly penetrating the cop from the inside.

According to my invention I place the cop, after winding, upon a bleaching spindle or spool the external diameter of which is smaller than that of the hole in the cop, providing for a clear annular space all around between the cop and the spindle or spool, and I then place the spindles or spools, with the cops upon them, in a vessel or vat, wherein they are acted upon by the bleaching or other liquid, and thus provide for the ready and simultaneous access of liquid to the interior and exterior of the cops, and allow the cops to be freely penetrated by the liquid.

The invention further consists in the combination, with a cop and its winding-bobbin, of a bleaching-spindle having a smaller external diameter than said bobbin.

The invention also consists in novel devices for transferring the cops from the bobbins on

which they are wound to the smaller spindles or spools.

In the accompanying drawings, Figure 1 represents a longitudinal section of a bobbin upon which the cop is wound, and Fig. 2 is an end view thereof. Fig. 3 is a longitudinal section of a tubular device which I employ in transferring the cops from the winding-bobbins to the bleaching-spindles, and Fig. 4 is an end view thereof. Fig. 5 is a side view of a bleaching-spindle, and Fig. 6 is an end view thereof. Fig. 7 is a longitudinal section of a cop, the bobbin on which it is wound, the tubular device for transferring it, and a side view of the bleaching-spindle, showing the manner of transferring the cop. Fig. 8 is a longitudinal section of a cop and a side view of a bleaching-spindle on which the cop is placed, and Fig. 9 is a plan of the cop and bleaching-spindle.

Similar letters of reference designate corresponding parts in all the figures.

In bleaching cops I take the fiber after it has been carded, drawn, and somewhat twisted, and I wind the roving or yarn upon a tubular bobbin, A, which may be made of wood, earthenware, glass, ebonite, or other material, and highly polished externally. The ends of the tubular bobbins A should be so shaped as to readily engage with the winding frame or machine, and in the present example of my invention are notched at a.

B designates the bleaching-spindle, which may be made of wood or other material calculated to resist more or less the corrosive action of the bleaching or other liquid. This spindle has at the lower end a base or foot, B', and it is considerably smaller in diameter than the exterior of the bobbin A, so that it can be readily inserted into the hole in the cop after the latter is slipped off the bobbin A. The bleaching-spindle B may have longitudinal external flutes, corrugations, or grooves, b; but I do not consider these necessary; and it may also have a hole or bore at the center to enable it to fit the spindle or skewer of a spinning-frame, in which the cops, with the spindles B in them, may be placed after bleaching and drying.

In transferring the cop from the tubular bobbin A, on which it is wound, to the bleaching-

spindle B, I may employ the device shown in Figs. 3 and 4, which consists of a tube, C, having at one end an extension, C', of smaller diameter.

5 The tube C should be externally somewhat less in diameter than the external diameter of the bobbin A, and of a size to freely receive the spindle B within it, and the tubular extension C' should be externally of a size to fit 10 easily in the tubular bobbin A. The tube C C' may be made of metal or other material.

In transferring the cop D from the winding- 15 bobbin A and onto the bleaching-spindle B, I place the bleaching-spindle inside the tube C, and insert the tubular extension C' into the bobbin A, all as shown clearly in Fig. 7. By a downward pressure or pull the cop D is then drawn off from the bobbin A and onto the tube C, as shown in dotted outline in Fig. 7, on 20 which it fits loosely because of the tube being externally smaller in diameter than the bobbin A. The tube C is now lifted off, leaving the cop D on the spindle B, whereon it fits very loosely, as shown in Figs. 8 and 9, a clear annular space, c, being left all around between the cop and the spindle throughout the entire 25 length of the cop.

Although the cop may be very readily transferred from the winding-bobbin to the bleaching-spindle by the aid of the tube C, it may be done in various other ways. The cops are now ready to be bleached by any one of the simple methods practiced in bleaching yarn in hanks. The bottom of the vessel or keir may 30 be first completely covered with spindles having cops upon them, and which may stand upright, side by side, a free space being left below them by means of a perforated false bottom, as usual. Then, if hanks are to be bleached 35 40 at the same time, the spindles may be covered with a layer of hanks. Then I arrange a second layer of spindles, and so on alternately until the vessel or keir is filled.

In case cops alone are to be bleached, the 45 several layers of spindles may be separated by perforated trays, and the last layer of spindles is covered with a weighted perforated tray or with ordinary packing-cloth or other substance. The washing, bleaching, and drying now goes 50 on in the usual well-known way as in bleaching hanks. In case keirs are used, which can be hermetically closed—as, for instance, in the case of a vacuum apparatus—the whole process may be considerably shortened, producing 55 a great improvement in the bleaching of the fiber by enforcing the discharge of the bleaching or washing liquid by means of air-pressure produced either by an air pump or injector. In such case the presence of air reduces 60 greatly the development of gaseous chlorine.

When a bluish or other tinge of the yarn is desired the cops, instead of going after the

bleaching to the drying-room, are once more put into the bleaching vessel or keir, arranged 65 as before described, and are soaked with a solution of indigotine or other desired coloring-matter. They may be then removed and freed from water by the action of a centrifugal machine or otherwise, and taken to the drying- 70 room. Any irregularities in the bluing disappear entirely in the finished cops by reason of the many doublings that take place in the further spinning of the sliver.

I am aware that it is old to bleach and dye 75 cops by placing them upon hollow perforated skewers or spindles which communicate at their ends with a pipe through which the bleaching or dyeing liquid is injected or forced 80 into the hollow skewers or spindles, and thence 85 into the cops; and I am also aware that such skewers or spindles have been fluted or grooved in order to better expose the interior of the cops to the action of the liquid; and I do not 90 therefore claim broadly the placing of the cops on separate spindles for bleaching or dyeing. In this old method, however, the cops fit snugly 95 on the skewers or spindles, and even though the latter be fluted or grooved the swelling of the yarn when wet will cause it to be drawn 100 tightly upon the ridges between the flutes or grooves and kept at a tension across the flutes, and thereby the cop will be compacted internally to such an extent as to prevent the liquid from rapidly, thoroughly, and uniformly penetrating all parts of the cop, as it can both from the interior and exterior simultaneously when a clear annular space is left all around between the cop and spindle, and the cop fits very loosely on the spindle even when wet, as 105 in my case.

What I claim as my invention, and desire to secure by Letters Patent, is—

1. The method of bleaching or dyeing cops, consisting in placing the cop, after winding, 110 upon a bleaching spindle or spool which has an external diameter less than that of the hole in the cop, providing for a clear annular space all round between the cop and spindle or spool, and then placing the spindle or spool, with the 115 cop upon it, in a vessel, wherein it is subjected both internally and externally at the same time to the action of bleaching or other liquid, substantially as herein described.

2. The combination, with a cop and its winding-bobbin A, of a bleaching-spindle, B, having a smaller external diameter than said bobbin, substantially as herein described.

3. The combination, with the winding-bobbin A and spindle B, of the tube C, with the extension C', substantially as herein described.

EMANUEL RUSCH.
